UNITED STATES PATENT OFFICE.

EDWARD H. ALLING, OF ROGERS PARK, ASSIGNOR TO THE L. H. THOMAS COMPANY, OF CHICAGO, ILLINOIS.

STOPPER AND POURING-NOZZLE FOR INK-BOTTLES.

SPECIFICATION forming part of Letters Patent No. 432,924, dated July 22, 1890.

Application filed March 17, 1890. Serial No. 344,104. (No model.)

To all whom it may concern:

Be it known that I, EDWARD H. ALLING, a citizen of the United States, residing in Rogers Park, in the county of Cook and State of Illinois, have invented a new and useful Improvement in a Combined Stopper and Pouring-Nozzle for Ink-Bottles, of which the following is a specification.

The object of my invention is to provide a combined cork or stopper and pouring-nozzle for ink-bottles of a simple and cheap construction, which may be easily and rapidly inserted in the bottle and operated to close the same liquid-tight with certainty, and through the pouring nozzle or spout of which the ink may be poured in small quantities without danger of dripping or soiling the top of the bottle or pouring-nozzle.

To this end my invention consists in a metallic tube or pouring-nozzle, preferably made of britannia metal, pewter, or other soft metal or metal alloy, in combination with an annular tapering cork surrounding such metallic tube, and to which it is rigidly and firmly fixed by shoulders or flanges formed on the metal tube. The upper end of the metal tube or pouring-nozzle is furnished with a screw-thread and with a threaded cap for closing the same, and the extreme end of the pouring nozzle or tube is furnished with an internal flange, which serves to divide or cut the stream when the bottle is tipped upward, so as to prevent drops of the liquid from dripping from or adhering to the outside of the pouring-nozzle, and thus smearing and soiling the same, as well as the screw-cap or the fingers in closing the screw-cap. I find that by furnishing the pouring-nozzle with this internal lip or sharp internal flange it serves to cut or divide the flowing stream of liquid clearly, so that one portion flows back into the bottle and the other portion drops into the inkstand without any tendency of the liquid to cling to or smear the pouring-nozzle. This internal flange also affords a smooth finish to the end of the pouring-nozzle and serves to strengthen and protect the same.

In the accompanying drawings, which form a part of this application, and in which similar letters of reference indicate like parts,

Figure 1 is a side elevation of an ink-bottle embodying my invention. Fig. 2 is a sectional view showing the bottle closed; and Fig. 3 is an enlarged sectional view of the metal tube, showing the same before the flange or shoulder is formed upon the lower end of the tube.

In the drawings, A represents an ink-bottle, B the metallic tube or pouring-nozzle, and C the annular tapering cork surrounding the same. The metal tube is furnished with a collar or shoulder b, which fits upon the upper end of the annular cork, and a flange or shoulder b' is turned upon the lower end of the tube B after the tube is inserted through the annular cork for the purpose of rigidly securing the cork and tube together. It will be observed that the shoulders b and b', fitting against the opposite ends of the annular cork, serve to combine and fix the cork and tube rigidly together. The upper shoulder or collar b serves not only as a means of combining the tube and cork rigidly together, but it also affords a bearing for the annular driving-tool in driving the combined stopper and pouring-nozzle into the bottle. The upper shoulder b should be made slightly smaller in diameter than the mouth of the bottle, so that this plate b may be driven down flush with the upper edge or surface of the bottle-neck, as is clearly shown in Figs. 1 and 2. It thus gives a neat finish to the bottle as a whole and produces a firmer, closer, and stronger union or fit between the cork and the neck of the bottle. The upper end of the metal pouring tube or nozzle B is furnished with screw-threads b², which engage the corresponding threads f of the screw-cap F, by which the mouth of the pouring-nozzle is closed. The screw-cap F is furnished with an elastic gasket or packing-plate f' to effect a perfect closure of the pouring-nozzle. The pouring-nozzle is provided with an internally-projecting flange b³ at its upper end, which serves to divide the stream in pouring and prevent the ink from dripping or smearing the pouring-nozzle on the outside. The metallic pouring-tube, it will be observed, extends entirely through the cork-ring C throughout its length, and also affords a perfectly-smooth bore or tube for the flow of the ink.

After the bottles are filled with ink my compound stopper and pouring-nozzle may be driven or inserted in the bottles very easily, and when so inserted it is a perfectly-safe closure of the bottle. The internal flange b^3 also affords a smooth even seat for the gasket or packing f' , so that the screw-cap F will make a perfectly-tight closure with the pouring-nozzle. When the cork C is driven into the bottle, so that the collar b enters the mouth of the bottle flush with its upper edge, as shown in Fig. 2, the collar b will cut or shave a narrow annulus c off the corner of the cork and make a perfect seal of the bottle by the forcible compression of the material of the cork between the edge of the collar b and the wall of the bottle-neck.

I claim—

1. The combination, with an ink-bottle, of an annular cork C, a metal pouring-tube B, having an annular shoulder or collar b and a flange b' , embracing the ends of said annular cork and rigidly securing the same to said tube, said flange b' being turned on the lower end of said tube after it is inserted through said cork, said pouring-tube having a nozzle portion projecting above said shoulder b , provided with screw-threads b^2 and an internal

flange b^3 , and a screw-cap F, having a packing f' , substantially as specified. 30

2. The combined ink-bottle, stopper, and pouring-nozzle, consisting in the combination, with annular cork C, of pouring-tube B, extending through said cork and provided with external shoulders $b b'$, engaging the ends of 35 said cork, said shoulder b' being turned upon the lower end of said tube after it is inserted through said cork, and a screw-cap F, fitted on the threaded end of said pouring-tube which projects above said shoulder b , substantially 40 as specified.

3. The combination, with the bottle A, of the cork-shell C, metal pouring-tube B, having upper collar b adapted to fit within the neck of the bottle flush with the upper edge 45 or surface thereof and seal the bottle by cutting or shaving off a narrow annulus of cork between itself and the corner of the bottle-neck, said pouring-tube projecting above said shoulder b , and having a screw-threaded cap, 50 substantially as specified.

EDWARD H. ALLING.
